UNITED STATES PATENT OFFICE.

ARVID W. EKBERG, OF JAMESTOWN, NEW YORK.

GRAVITY-LOCK.

Specification of Letters Patent. Patented Feb. 11, 1913.

1,053,124.

Application filed March 30, 1911. Serial No. 617,890.

To all whom it may concern:

Be it known that I, ARVID W. EKBERG, a citizen of the United States, residing at Jamestown, in the county of Chautauqua and State of New York, have invented certain new and useful Improvements in Gravity-Locks, of which the following, taken in connection with the accompanying drawings, is a full, clear, and exact description.

The invention relates to door locks and the objects of my improvement are, first, to provide a gravity lock for fire-proof swing doors which is positive or absolute in its action, so that intense heat cannot cause failure of locking action, and toward this end there is entire omission of all springs or parts whose power to act could be overcome by intense heat; and second, to provide a plurality of novel locks operable from a common center or master lock and from either side of the door. The action of the lock is accomplished entirely by a weight and bell-crank over which intense heat has no effect. The lock is shown applied to a door of sheet metal construction in which the hollow sheet metal gives ample room for the action of the parts. It is apparent, however, that a wooden cored, or sheeted door may be channeled along the face of the stile to allow use of the connecting parts of the plurality of locks within the door, and also within the door jamb for the keeper mechanism; or the parts may be applied with a casing suitable for attachment on the outside of the door, the same as a rim lock. The plurality of locks are rendered necessary in order to securely hold the door along its front edge very much as it is held along the rear edge by its hinges, as against the warping power of intense heat. It is apparent that if the door was only locked at one point midway of its height, the upper and lower corners of a metallic door might be warped out of shape by the intense heat and thereby allow the flames to enter through the opening so made. This would destroy its fireproof quality. By arranging a plurality of locks or latches at the side, top, or bottom of the door, this danger is entirely overcome.

In the drawings, Figure 1 is a sectional view at line X X in Fig. 2, showing the arrangement of the lock; Fig. 2 is a vertical sectional view of the door edge through a

series of locks and showing the latches and keepers for the bolts; Fig. 3 is a sectional view of one of the latches at line Y Y in Fig. 2, showing the keepers and the bolt in normal locked position; and Fig. 4 is a similar sectional view showing the gravity action of the latches or keepers in the process of engaging the bolt. Fig. 5 is a sectional view at line Z Z of the latch at the top of the door.

Like numerals of reference refer to corresponding parts in the several views.

The numeral 10 indicates the door, and the numeral 11 the edge of an adjacent door, door jamb or casing, which parts are here shown as constructed of hollow sheet metal, and the bolt and latch or keeper mechanisms are inserted within the same in suitable openings in the edges of the parts.

The lock is preferably composed of a plurality of parts according to the size and more particularly the height of the door. Doors for fire walls in shops and foundries oftentimes reach the height of 12 to 15 feet. For such doors it is apparent that a series of auxiliary locks are necessary above, and sometimes below the main lock 12. Thus, for example, in an extra large door the main lock 12 is placed at the usual height, additional locks 13 may be arranged along the edge of the door as needed and a lock 14 is placed at the top of the door. A lock similar to lock 13 may be placed below lock 12 and operated in a manner hereinafter set forth.

The main lock 12 is provided with a bolt 15 which is made in the form of an enlarged plate 16 within the casing 17 of the lock. An opening 18 is provided in plate 16 having a straight side 19. A cross shaft 20 extends through lock 12 through opening 18 and a roll-back plate 21 is attached to shaft 20 within opening 18. The plate 21 is considerably smaller than opening 18 except upon the side 19, which plate 21 bears squarely against so that when shaft 20 is turned in either direction by means of knob 22, plate 21 will cause bolt 15 to move toward the rear of the lock, thereby withdrawing bolt 15 within the door 10. The lock 12 is connected to and operates locks 13 and 14 by means of a double bell crank 23, which is pivotally attached to the casing 17 and 24, and the rod or link 25 is pivotally attached to an arm of bell crank 110

23 at 26 and extends to bell cranks 31 in locks 13 and 14.

The lock 14 consists of the upper end of rod 25, which is formed in the shape of a bolt 27 and has a latch or keeper 28 pivotally attached within the casing 29 by the pin 30.

The locks or latches 13 consist of the bell cranks 31 which are pivotally attached at 32 to the casing of the lock 13 and at 33 to rod 25 and at 34 to a bolt 35.

The double bell crank 23 has an arm 36 extending up therefrom and slidably engaging beneath a strap 37 or within an opening in the plate 16 of bolt 15. A second rod 38 is pivotally attached at 39 to the opposite end of crank plate 23 and bears thereon the weight 40 which weight must be sufficiently heavy to operate the parts and hold the bolts firmly in position. The rod 38 may only support the weight 40 or may be extended to a lock or locks in the lower portion of the door similar to locks 13 or 14. A staple 41 is provided through which rod 38 extends to guide the weight 40 as it moves up and down. The weight 40 is sufficiently heavy to normally hold the bolts 15, 35 and 27 in the extended position beyond the edge of the door 10 and the only manner in which said bolts can be withdrawn from this normal position is by turning knob 22 and shaft 20, thereby simultaneously operating the cranks 23 and 31 through rod 25 and withdrawing the bolts 35 from their extended position. It is obvious, however, that when said bolts are so withdrawn as soon as the shaft 20 is released the weight 40 will cause the cranks and bolts to return to said normal position. It is also apparent that the links 25 and 38 may be extended and pivotally attached to any series of locks along the edge of the door and that the outer ends of said links may be used as bolts for latches or keepers at the top or bottom of the door. The bell crank 23 is preferably of sufficient length and the weight 40 of sufficient size to give weight 40 a powerful leverage upon the operating parts so that they will act surely and quickly. The sides of the casing for lock 12 form stops for the plate 16 which limit the movement of the bolt 15 and of the other parts of the series of locks.

The bolts 15 and 35 are engaged and held 55 by keepers or latches 42 and 43 which are pivotally mounted a spaced distance apart on the adjacent double door or door jamb 11. The upper keeper 42 is pivotally attached to the supporting plate at 44 at its rear end and the front end has a downwardly projecting catch 45 to engage the front corner of the bolt 15 or 35. The lower keeper 43 is pivotally attached at 46 to the supporting plate and has an upwardly extending front catch 47 to engage the front

side of bolts 15 or 35. The oppositely inclined rear ends of these two keepers are turned toward one another in order to preserve a straight draw on the bolt so that the catches 45 and 47 will not slip or draw off from the bolt, but will preserve a positive engagement therewith. Each of the keepers 42 and 43 have an inclined front face to the catches 45 and 47 which is engaged by the rear side of the bolt as the door is closed, the inner edges of the bolt are rounded so that as the bolt strikes the inclined faces of the keepers it will press the two keepers apart and pass between the same. It is apparent that the upper latch 70 42 will fall of its own weight and its front end is caught by an inwardly projecting lip 48 on the door, which lip holds it in position when the bolt is withdrawn. The lower keeper 43 is operated by a weight lever 49 which is pivotally attached at 50 to the supporting plate and has a leverage on the under side of latch 43 to allow the latch sufficient movement to escape the bolt as it presses through between the latch parts, the outer end of latch 43 engages a lip 51 on the door similar to lip 48 and for a similar purpose. The single latch or keeper 28 in lock or latch 14 is all that is necessary to hold bolt 27 on the upper end of rod 80 35 at the top of the door. The casing or door 11 has an opening 51 in its edge which allows the bolt to enter between the latches 42 and 43 while held in the extended position by weight 40. It is obvious that either 90 of the bolts 15 or 35 while thus firmly held will press the two latches apart and that when the latches return to normal position because of their gravity action, the bolt will be securely caught by said keepers and 95 cannot be withdrawn except when it is moved by means of turning knob 22. Thus the bolt can enter between the two latches but cannot escape therefrom as long as it extends beyond the edge of the door. 100

In order to lock the entire series of bolts in the extended position so they cannot be withdrawn by turning knob 22, a cylinder lock 52 with bolt 53 is provided in lock 12 so that bolt 53 may be inserted by the operation of the lock 52 between the inner end of plate 16 and the side of the casing around the lock 12, thereby preventing the movement of the plate 16 and all the bolts of the different locks. 110

It is apparent that either one of the latches 42 or 43 would alone be sufficient to hold either one of bolts 15 or 35 nearly as well as the two keepers. Such a modification would not depart from my invention. 120

The keepers or latches take the place of a striking plate on the door jamb or adjacent door as in double doors, and the engagement of the bolt is entirely within this striking plate or latch, thus departing en- 125 130

tirely from the usual form of latches or locks as used upon doors at the present time.

In order to withdraw the bolts from their extended position it is apparent that the links 25 and 38 will invariably have a pulling strain as they are actuated by the master lock 12. This is essential since if a pushing strain were necessary to withdraw these bolts in order to unlock the door in times of intense heat when the rods become so heated that they will bend and turn, it is apparent that the pushing strain would cause the links to bend and thereby block the action of the lock, rendering the operator unable to withdraw the bolts. With my arrangement of these bolts and link connections so that there is invariably a pulling strain it is obvious that no such mishap can occur. It is also obvious that all these parts may be attached to the outside of the door and a suitable casing provided for them so that they may be attached to any form of door.

25 I claim as new:

1. A latch comprising a slidably mounted bolt, said bolt having an opening therein, a shaft extending through said opening, a roll-back plate attached to said shaft within said opening to manually operate said bolt by turning said shaft, a bell crank connected to said bolt, and a weight pivotally hung from one arm of said bell crank to hold said bolt in the extended position.

35 2. A latch comprising a slidably mounted bolt, said bolt having an opening therein, a shaft extending through said opening, a roll-back plate attached to said shaft within said opening to manually operate said plate by turning said shaft, a bell crank connected to said bolt, a weight pivotally hung from one arm of said bell crank to hold said bolt in the extended position, and suitable means for locking said bolt in the ex-
40 tended position.

45 3. A latch comprising a slidably mounted bolt, said bolt having an opening therein,

a shaft extending through said opening, a roll-back plate attached to said shaft within said opening to manually operate said plate 50 by turning said shaft, a bell crank connected to said bolt, a weight pivotally hung from one arm of said bell crank to hold said bolt in the extended position, and a key actuated bolt to lock and hold said 55 slideable bolt.

4. A multiple latch comprising a plurality of slidably mounted bolts, a suspended weight to hold said bolts normally beyond the edge of the door and return them 60 to that position when withdrawn, suitable means for keeping said bolts, and means in the central latch for manually withdrawing all of said bolts from said keeping means 65 and raise said weight.

5. A multiple latch consisting of a plurality of slidably mounted bolts, bell cranks connected to said bolts to slidably move the same, link connection for said bell cranks, a weight on one of said bell cranks to actuate 70 said bolts in one direction, and means for manually actuating said bell cranks in the opposite direction.

6. A multiple latch comprising a plurality of gravity actuated bolts, bell cranks 75 connected to said bolts to slidably actuate the same, links connecting said bell cranks, a shaft and knob for manually turning one of said bell cranks to thereby withdraw all of said bolts, a weight on one of said links 80 to return said bolts to a normally extended position beyond the edge of the door, and suitable keepers for said bolts having openings to receive said bolts when in the extended position, substantially as and for the 85 purpose specified.

In testimony whereof I have signed my name to this specification in the presence of two subscribing witnesses.

ARVID W. EKBERG.
